UNITED STATES PATENT OFFICE.

ANDERS H. KOPPERUD, OF OAKLAND, CALIFORNIA.

GRADING APPARATUS.

1,379,633.

Specification of Letters Patent. Patented May 31, 1921.

Application filed January 5, 1920. Serial No. 349,389.

To all whom it may concern:

Be it known that I, ANDERS H. KOPPERUD, a citizen of the United States, residing at Oakland, in the county of Alameda and 5 State of California, have invented certain new and useful Improvements in Grading Apparatus, of which the following is a specification.

In the modern construction of road building, and more particularly State highways, or that type of roadways having a permanent base, such as concrete or the like, and which may or may not be surfaced with other material, such as asphalt or oil surface dressing, it has been found expedient, owing to the expense attached to the building or construction of such roadways to construct the same as narrow as is consistent with the road travel thereover, and generally this has been of a width sufficient to permit the passage of two vehicles. This width of the constructed roadbed is such as to provide what may be termed a central strip of finished roadbed throughout the 15 length of the roadbed, leaving at each side thereof a considerable width of dirt roadway. It has been found, and, in fact, one of the main objections to such constructed roadways is that during the rainy reason 20 the water permeating the dirt side extensions of the finished roadway creeps or works beneath the bottom or bottom layer of the finished roadway at the side edges thereof and undermines or washes out the 25 dirt bed thereunder and thereby weakens the roadway at the side edges thereof to such an extent that heavy travel thereover at the side edges of the roadbed will cause a breaking of the finished roadway at such side 30 edges.

This widening or extension of the width of a finished roadbed has heretofore been accomplished by digging trenches at the sides of the finished roadbed, which ditches 35 have been dug by hand and extend for the entire length of the roadway, and they are approximately two to two and one-half feet in width and of a suitable depth, the cost entailed in the construction of said ditches 40 being considerable, and therefore the present invention has for its principal object to provide means whereby these ditches for the side extension of the finished roadway 45 may be rapidly, easily and cheaply constructed.

The invention has for its principal object to provide an attachment or cutting blade, preferably with guiding means, which is adapted for mounting on a vehicle and whereby the vehicle, as the same is drawn 50 or propelled longitudinally of the roadway, will cut or dig said ditch and remove the earth therefrom, thereby expediting the construction of the ditch and materially reducing the cost thereof by dispensing with 55 a number of laborers, which are necessary when the ditch is dug by hand. To provide a construction particularly adapted for attachment to a road-scraper or grader of the type generally used in road building, thereby enabling the use of the road-scraper in 60 constructing the ditch.

To more fully comprehend the invention, reference is directed to the accompanying drawings, wherein—

Figure 1 is a view in side elevation of the preferred embodiment of my invention as applied to a conventional form of road-scraper.

Fig. 2 is a view in detail of the embodiment of my invention illustrated in Fig. 1, and illustrating the manner of attaching the same to the road-scraper blade.

Fig. 3 is a view of a modified form of the construction.

Fig. 4 is a cross sectional view of a roadway illustrating a ditch formed at one side thereof and prior to being filled with rock, gravel or the like, which provides an extension for the side of the constructed road.

Fig. 5 is a diagrammatic view of the invention.

Referring more particularly to the drawings, wherein like characters of reference designate corresponding parts—1 indicates 95 a supporting frame of any suitable type of road-machine mounted on wheels 2 and preferably of the horse-drawn type. The frame 1 carries a suitable sub-frame 3 capable of rotation on a vertical axis beneath 100 the pivotally mounted draw bar 4, and said sub-frame and draw-bar are adapted to be raised and lowered to vary the relative position of the sub-frame relatively to the bearing points of the wheels 2.

To accomplish this vertical attachment any suitable means may be provided, that form illustrated including a link 5 connected with the arms 6 of a lever 7 pivotally supported as at 8 on the frame 1, and which 110

lever is retained in its adjusted position by a suitable dog 9, engaging the teeth 10 of a segment 11.

Depending from the under edge of the 5 sub-frame 3 are the blade supporting arms 12 to which are secured, in any suitable manner, the usual scraper blade 13 which is disposed preferably in a horizontal plane, the blade being concaved in form and of any 10 suitable length and width. To the lower edge of the blade, which normally mounts the removable cutting edge, is detachably secured the cutting edge or member 14 of a length considerably shorter than that of the 15 blade 13, and so positioned that the forward end 15 of said cutting edge is removed a short distance from the forward end of the blade 13, and the rear end of said cutting edge terminates approximately midway of 20 the length of said blade 13 thereby providing a cutting edge for the blade which projects a slight distance below the lower edge 16 thereof and the ends of which terminate one adjacent the forward end of the blade 25 and the other approximately midway of the length of the blade. The rear end of the cutting edge 14 is preferably at its lower corner bent or curled upwardly and forwardly, providing a millboard or member 17 30 for furrowing the material removed from the ditch during the formation thereof.

At the rear of the front end 15 of the cutting edge 14 is secured a suitable angle plate or member 18, the rear leg 18' of 35 which extends to the rear of the cutting edge and is inclined rearwardly from the front end 15, said leg during the forming of the ditch resting on the vertical wall 19 of the road base 20, (Fig. 4 of the drawings) providing with said wall 19 a guide to assist the operator in making a clear excavation of the material adjacent the highway side wall.

Depending downwardly from the blade 40 13 at a point in advance of the front end 15 of the cutting blade 14 is a depth regulating shoe 21, the lower end of which is curved rearwardly and is adapted to rest during the formation of the trench on the 45 upper surface of the road-base 20 adjacent the vertical edge 19.

In Fig. 3 I have illustrated a modified form of trench forming blade, wherein the depth shoe 21' and the guide leg 18' are 50 formed integral with the body of the blade 14, thus materially reducing the cost of manufacture, and reducing the time consumed in applying and detaching the trench forming blade relative to the member 13.

60 In operation, reference being had particularly to Figs. 1, 4 and 5 of the drawings, my improved device operates in the following manner:—The sub-frame 3 is rotated on the supporting beam 4 to dispose 65 the scraper 13 and trench forming blade 14

at the desired angle, dependent on the width of the trench it is desired to cut, the greater the angle of blade 13 relatively to the direction of travel of the vehicle supporting the same the greater the width of 70 the trench. The lever 6 is operated to lower the trench forming member to rest on the road surface adjacent the side 19 of the road base 20. The implement is then 75 propelled longitudinally of the road, as in Fig. 5, with the shoe 21 resting on the upper surface of the road base and the arm 18 resting on the vertical side 19 of the road base, and in this position the trench forming member 14 cuts the trench the desired 80 width and depth; the millboard 17 assists in discharging the material excavated from the trench therefrom, and the portion or tail 16 of the scraper blade 13 removes the excavated material from the trench to a 85 point a considerable distance from the side of the formed trench.

It is to be understood that various changes in the form, proportion, size and minor details of construction of the herein described 90 invention within the scope of the claims may be resorted to without departing from the spirit or sacrificing any of the advantages of the invention.

Having thus described my invention, 95 what I claim as new and desire to protect by Letters Patent is:—

1. An apparatus for excavating a trench at the side of a permanent highway base, the same comprising a vehicle, a blade supporting member rigidly suspended therefrom, means between the blade and vehicle and adapted for operation to permit of angular adjustment relatively to the direction of travel of the vehicle and laterally relatively to the highway base, an excavating member depending rigidly from the lower edge of the blade, guide means associated with the forward end of the member for riding on the side edge of the highway base, 100 and a shoe associated with said member in proximity to said guide means for riding on the surface of the highway base to limit the depth of cut of said member. 105

2. An apparatus for excavating a trench 110 at the side of a permanent highway base, the same comprising a vehicle, an excavating member carried thereby, guide means carried by said member for riding on the side edge of said highway base, to permit a sliding movement between the forward end of the excavating member and the side edge of the highway base, and a shoe carried by said member above said guide means for riding on the surface of said highway base 115 to limit the depth of cut of said member.

3. An apparatus for excavating a trench 120 at the side of a permanent highway base, the same comprising a vehicle, a rigid excavating member depending therefrom and 125

- including a horizontally disposed blade, means for permitting the adjustment of the member at an angle to the direction of travel of said vehicle, said blade provided 5 on its lower edge intermediate of its ends with a depending cutting edge, the forward end of which falls short of the forward end of the blade, a shoe positioned in advance of the direction of travel of the cutting edge 10 for resting on the surface of the permanent highway base to limit the depth of cut of said edge, and a guide member extending rearwardly from the front end of said cutting blade for riding on the side wall of 15 said highway base to provide a means for permitting a relatively easy sliding movement between the forward end of the cutting member and the side of the highway base.
- 20 4. An apparatus for excavating a trench at the side of a permanent highway base,
- the same comprising a vehicle, an excavating member carried thereby and including a horizontally disposed blade arranged at an angle to the direction of travel of said vehicle, said blade being provided intermediate of its ends with a depending cutting edge, a portion 25 of said blade in advance of the end of said cutting edge adapted for overlying the highway base and the portion of said blade 30 extending beyond the rear end of said cutting edge adapted to overlie the ground surface and to spread the material excavated by said blade over the ground surface.

In testimony whereof I have signed my 35 name to this specification in the presence of two subscribing witnesses.

ANDERS H. KOPPERUD.
